FOREIGN PATENT DOCUMENTS

CN 309121688 S 2/2025

Primary Examiner — Cynthia R Underwood

(74) Attorney, Agent, or Firm — Hawaii Patent Services;
Nathaniel K. Fedde; Kenton N. Fedde(57) **CLAIM**

The ornamental design for a cable organizer, as shown and described.

DESCRIPTION

FIG. 1 is a front, right, bottom perspective view of a cable organizer, showing my new design;

FIG. 2 is a rear, left, top perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of detail 9 in FIG. 7.

The dash-dot-dash broken lines are for notating enlarged views and form no part of the claimed design.

1 Claim, 9 Drawing Sheets(56)
